UNITED STATES PATENT OFFICE

JOHN D. BURGER, OF RYE, NEW YORK

DESIGN FOR A TOBACCO PIPE

Application filed May 4, 1933. Serial No. 48,014. Term of patent 14 years.

To all whom it may concern:

Be it known that I, JOHN D. BURGER, a citizen of the United States, residing at Westchester Country Club, Rye, county of Westchester, and State of New York, have invented a new, original, and ornamental Design for a Tobacco Pipe, of which the following is a specification, reference being had to the accompanying drawing forming part thereof.

In the drawing

Fig. 1 is a side elevation;
Fig. 2 is a top plan view; and
Fig. 3 is an end elevation.

I claim:

The ornamental design for a tobacco pipe, substantially as shown.

JOHN D. BURGER.
